UNITED STATES PATENT OFFICE.

JEAN BAPTISTE DAUDELIN, OF FALL RIVER, MASSACHUSETTS.

SHUTTLE.

Application filed February 27, 1926. Serial No. 91,244.

This invention relates to hand threading loom shuttles, and particularly to a thread-tensioning device therefor. According to my general concept, the tensioning device is constructed as a gravitating member under which the thread is drawn and by which a uniform tension is maintained thereon. Structurally, my tension device may take a variety of forms and may be either combined with the eye-piece of the threading eye or may be used independently thereof, both arrangements being shown herein for purposes of disclosure.

My invention also involves certain improvements in the construction of the eye-piece for the threading eyes of the shuttle, as will appear more particularly herein-after.

The construction and operation of my invention, together with selected embodiments thereof illustrative of the principles involved, are described and shown in the accompanying specification and drawings, and the characteristic features of novelty are particularly pointed out in the appended claims. In the drawings:

Fig. 1 is a plan view at the threading end of a standard shuttle equipped in accordance with my invention.

Fig. 2 is a section on the line 2—2, of Fig. 1.

Fig. 3 is a detail view of the eye-piece for the threading eye, removed.

Fig. 4 is a detail view of the gravitating tensioning device removed.

Fig. 5 is a detail view of the cooperating tension plate used in the shuttle shown in Fig. 1, and

Fig. 6 is a view similar to Fig. 1 and showing a modification.

I have indicated at 1 the body of a hand-threading loom shuttle of conventional type, at 2 the bobbin chamber thereof, at 3 the shuttle throat, and at 4 the curved threading slot which extends from the bobbin chamber forwardly across the upper face of the shuttle and backwardly along the side wall of the slot and into the delivery end of the threading eye 5 of the shuttle.

The eye 5 is a cylindrical bore extending transversely of the shuttle throat. The wood of the shuttle at that side of the eye farthest removed from the bobbin chamber is counterbored to provide a keyway disposed parallel to the threading eye and ex-

tending transversely of the shuttle throat. Press-fitted within the eye bore 5 is an eye-piece 7 which may be of any desired material, but is preferably of porcelain or like vitreous material which is hard and non-grooving. The eye-piece is shaped to fit the eye snugly at one end and is loose in the eye at its other end. This reduces the danger of the eye-piece being broken in the operation of the shuttle, as would occur if the eye-piece were to fit the eye snugly from end to end thereof.

In order to prevent rotation of the eye-piece in the eye, said piece is provided with a longitudinally extending rib 8 which fits within the counter-bore of the eye and keys the eye-piece within the eye. This rib 8 is interrupted between its ends by a notch 9. The upper side of the eye-piece is preferably cut away between its ends to permit direct passage of the thread T from the bobbin chamber into the notch 9 when the shuttle is being threaded. The notch 9 communicates with a downwardly and outwardly extending slot 10 disposed on the under side of the eye-piece and extending longitudinally along the eye-piece to the delivery end of the eye.

After the shuttle is threaded, the tension is maintained on the thread as it draws from the bobbin through the eye-piece by means of a gravitating tension device 11 which may be either set in the shuttle throat in advance of the eye-piece, as shown in Figs. 1 and 2, or may be positioned directly over the eye-piece, as shown in Fig. 6. Referring first to the form of tensioning device shown in Figs. 1 and 2, I preferably interpose between the tensioning device 11 and the floor of the shuttle throat a tension plate 12 which may be of glass or any other vitreous, non-grooving material. Where desired, one face of the wear plate may be roughened and the other face left smooth, so that by reversing the position of the plate a greater or lesser friction may be offered to the passage of the thread thereover, according to the character of the thread being run.

The tensioning device 11 may be a simple 105 conical button which is pierced at its apex to loosely receive the downwardly bent end of a positioning pin 13 which is driven vertically into the wood of the shuttle adjacent the shuttle throat. The pin 13 fixes the po- 110

sition of the tensioning device 11 in the throat, the loose connection between said tensioning device and pin permitting the tensioning device to be vibrated in a vertical plane by the thread as it is drawn therebeneath. Where a tensioning plate 12 is employed, the tensioning device 11 may have a downwardly extending tongue 14 formed on its lower side, which tongue is adapted 10 to be received in one or the other of a pair of oppositely disposed notches 15 in the lateral edges of the tensioning plate. The tongue 14 has a double function in that it not only maintains the plate and tensioning 15 device in proper relation to each other, but acts as a stop or guard for the thread when the shuttle is threaded, whereby to prevent the thread from sliding laterally past back into the threading slot 4.

20 Where the tensioning device is positioned over the eye-piece of the shuttle, as shown in Fig. 6, it is unnecessary to use a wear-plate as such, the flattened upper surface of the eye-piece serving as a wear and tension- 25 ing surface between which and the super- posed tensioning device 11 the thread is drawn. In this adaptation of my invention, the positioning pin 13 is preferably extended forwardly, and the cross-bar 16 thereof lies in substantially the longitudinal axis of the shuttle so as to be disposed across the inner end of the threading slot 4. So disposed, this portion of the pin constitutes a 30 guide assisting to deflect the thread into said slot in the threading action of the shuttle and a guard overlying said slot and effective to prevent the thread from jumping out of said slot in the run of the shuttle.

35 In the threading action of the shuttle, the thread is drawn through the threading slot past the end 8¹ of the rib 8 of the eye-piece 40 as a snubbing post. When threaded, the thread runs direct from the bobbin between the tensioning device 11 and the eye-piece or the tensioning plate 12, as the case may be, and out through the slot 10 of the eye-piece. The conical form of the tensioning device 45 prevents the thread from lifting upwardly therepast, and the tongue 14 thereof prevents escape of the thread laterally back into the threading slot 4. The thread is therefore compelled to run directly through the eye-piece.

50 Various modifications in the construction 55 and operation of my device may obviously be resorted to all without departing from

the spirit of my invention if within the limits of the appended claims.

What I therefore claim and desire to secure by Letters Patent is:

1. In a shuttle having a threading eye, a positioning pin disposed adjacent to said eye, and a gravitating tension device loosely guided on said pin and beneath which the thread is drawn into said eye and a depending 65 guard tongue on the tension device.
2. In a shuttle having a threading eye, a positioning pin disposed adjacent to said eye, and a conical gravitating tension device loosely guided on said pin and beneath 70 which the thread is drawn into said eye and a depending guard tongue on the tension device.
3. In a shuttle having a threading eye, a tension plate disposed beneath the path of 75 the thread to the eye and a gravity tensioning device disposed above said plate and co-operating therewith, said gravity device and plate having an interengaging projection and recess.
4. In a shuttle having a threading eye, a positioning pin disposed adjacent to said eye, a tensioning plate in advance of said eye, and a gravitating tension device loosely guided on said pin and between which and the tension plate the thread is drawn into 80 said eye, a depending tongue on said tension device, said tension plate having a recess receiving said tongue.
5. In a shuttle having a threading eye, a positioning pin disposed adjacent to said eye, and a gravitating tension device loosely guided on said pin, said tensioning device having a laterally disposed depending tongue constituting a guard effective to prevent 85 lateral escape of the thread therepast.
6. In a shuttle having a threading eye, a positioning pin disposed adjacent to said eye, a tension plate in advance of said eye, and a gravitating tension device loosely 90 guided on said pin and between which and the tension plate the thread is drawn into said eye, said tensioning device having a laterally disposed depending tongue constituting a guard effective to prevent lateral 95 escape of the thread therepast, and said plate having a notch to receive said tongue and co-operative therewith to maintain the tension device and tension plate in definite relation to each other.

In testimony whereof I affix my signature.
JEAN BAPTISTE DAUDELIN.
